3365

Conrad Seimel,
Design for Corners of Sheet Metal
Cans.

Fig. 2.

Original

CONRAD SEIMEL, OF GREEN POINT, ASSIGNOR TO CHARLES PRATT,
OF NEW YORK, N. Y.

Design No. 3,365, dated February 9, 1869.

DESIGN FOR THE CORNERS OF SHEET-METAL CANS.

The Schedule referred to in these Letters Patent and making part of the same.

To all whom it may concern:

Be it known that I, CONRAD SEIMEL, of Green Point, in the county of Kings, and State of New York, have invented a new and improved Design for Corners of Sheet-Metal Cans; and I do hereby declare that the following is a full, clear, and exact description thereof, which will enable others skilled in the art to make and use the same, reference being had to the accompanying drawings, forming part of this specification.

This invention relates to an improved design for the form of the corners of sheet-metal cans, calculated to strengthen the can, and present an ornamental appearance.

Figure 1 represents a front elevation of a portion of a can, formed according to my improved design, and

Figure 2 represents a horizontal section of a can.

Similar letters of reference indicate corresponding parts.

I propose to construct the said corners with ribs, A,

projecting outward in lines radiating from the centre, the outer surface being curved, while the side walls, from the termination of the said curvature, at *a*, are straight, or nearly so, to the point, *b*, of junction with the sides of the can.

The said sides are formed with a wide groove, B, on each side of the said projections.

The side walls of the projections, from *a* to *b*, may be either parallel with each other, or they may be divergent.

Having thus described my invention,
I claim as new, and desire to secure by Letters Patent—

The design for the corners of sheet-metal cans, herein set forth and shown.

CONRAD SEIMEL.
